UNITED STATES PATENT OFFICE.

BENJAMIN C. BARTLEBAUGH, OF WHEELING, WEST VIRGINIA.

BURNER.

1,173,547.

Specification of Letters Patent. Patented Feb. 29, 1916.

Application filed November 15, 1915. Serial No. 61,612.

To all whom it may concern:

Be it known that I, BENJAMIN C. BARTLEBAUGH, a citizen of the United States, residing at Wheeling, in the county of Ohio and State of West Virginia, have invented certain new and useful Improvements in Burners; and I do declare the following to be a full, clear, and exact description of the invention, such as will enable others skilled in the art to which it appertains to make and use the same.

This invention relates to improvements in gas burners for use either on heating or cooking stoves.

The primary object of the invention is to provide a burner of this character so constructed that a maximum quantity of air is fed with the gas fed to the burner, thereby insuring perfect combustion.

Another object is to construct a burner of this character so that the gas will be fed to the mixing chamber thereof with great force thereby carrying with it a large amount of air which causes a perfect mixing of air and gas in its passage to the burner proper thus assisting in producing perfect combustion.

Another object is to provide a burner with a mixing chamber having a distributing partition therein whereby gas and air is mixed a second time before admission.

Another object is to provide a burner having a plurality of rows of outlets on the top, said rows being arranged in series and the series spaced apart for the purpose of forming inlet channels for the air supplied to the flame while burning to assist in producing perfect combustion, and by means of which a flame is produced which destroys all poison which is contained in the gas such as carbon monoxid, all of the gases being consumed and thereby prevented from passing out to the surrounding atmosphere.

Another object is to provide a burner having a mixing chamber provided with inlets arranged to discharge thereinto in opposite directions to cause the streams passing therethrough to forcibly meet and thereby thoroughly mix the air and gas of which they are composed.

With these and other objects in view, my invention consists of certain novel features of construction, and the combination and arrangement of parts which will be herein-after more particularly described and claimed.

In the accompanying drawings: Figure 1 is a side elevation of a burner constructed in accordance with this invention; Fig. 2 is a vertical section thereof; Fig. 3 is a horizontal section taken on the line 3—3 of Fig. 2; Fig. 4 is a transverse vertical section taken on the line 4—4 of Fig. 2; Fig. 5 is a similar view taken on the line 5—5 of Fig. 2; Fig. 6 is a similar view taken on the line 6—6 of Fig. 2; Fig. 7 is a side elevation partly in section showing another form of burner; Fig. 8 is a transverse vertical section taken on the line 8—8 of Fig. 7; and Fig. 9 is a transverse horizontal section taken on the line 9—9 of Fig. 7.

The improved burner shown comprises an outer cylindrical casing 1 closed on all sides and at both ends, the ends of the cylinder being here shown extended outwardly in the form of a flange 2 over which the edges of the end closures 3 are crimped as shown clearly in Fig. 2. The upper or top portion of this casing is provided with a plurality of series of laterally spaced rows of perforations 4 extending from end to end of the burner, the space 4' between said series being designed to admit fresh air to the burning gas which passes through the perforations of each series, said perforations being designed to discharge gas from the burner, two series being here shown although obviously any desired number may be employed. This cylindrical casing 1 is shown provided in its bottom wall or the wall diametrically opposite the perforated wall thereof with an opening 5 for the admission of the fuel to the cylinder 1 in the form of air and gas as will be hereinafter more fully described. This lower wall is slit longitudinally and transversely and the slit portions thereof are bent to form the side walls 6 of a mixing chamber 7 to be described. As shown, this chamber 7 extends about one-half of the length of the cylinder 1, more or less, being spaced inwardly at its opposite ends from the opposite ends of said cylinder. As shown, the cylinder 1 is provided at its ends beyond the ends of the mixing chamber 7 with insets 8 and 9 which are here shown connected to the slit portions of the cylinder by crimping, (see Fig. 4). These insets 8 and 9 are in the form of laterally curved longitudinal extensions of semi-cylindrical shells 1^a and 1^b which are disposed within the casing 1 opposite the perforations there-

in. These shells 1^a and 1^b have the extensions 8 and 9 formed intermediately of the width thereof preferably midway, as shown in Figs. 2 and 3 and the inner opposed ends 5 of said shells are spaced apart to form the fuel inlet 5. The side edges of these shells are positioned to form supports for a horizontal partition 11 to be described, and are offset inwardly to form pockets 1^c to receive 10 flanges on said partition. These shells perform the double function of supports for the partition 11 and as reinforcing and strengthening means for the central portion of the casing 1. They also provide a closure for 15 the slit wall of the casing and as means for forming the opening 5 of the desired size, the distance between the inner ends of said shells controlling the size of said opening.

The bottom wall of the mixing chamber 7 20 which is here shown cylindrical but may be of any other desired cross sectional contour, is formed by inserting a longitudinally extending strip 10 which is here shown extended the full length of the chamber 7 and 25 is crimped to the edges of the outwardly bowed side walls 6 thereof by crimping.

Arranged within the casing 1 is the longitudinally extending horizontally disposed partition 11 which is disposed between the 30 series of perforations 4 and the opening 5 and which extends over said opening and projects beyond the end walls thereof. This partition 11 is shown provided on its opposite side edges with right angular depending 35 flanges 12 which may be secured to the opposed side walls of the cylinder 1 by soldering or in any other suitable manner, said partition being here shown supported by the edges of the shells 1^a and 1^b as above described, said edges being shown offset inwardly as at 1^c forming pockets to receive the flanges 12. This partition 11 is designed as a deflector or distributor for the air and gas admitted through the opening 5 40 which impinges against said partition and spreads outwardly toward the opposite ends thereof becoming thoroughly mixed in its passage and then passes up around said ends into the space between said horizontal partition and the perforated top of the cylinder and the so mixed air and gas then passes out through the perforations 4 where it is ignited and forms the flame of the burner.

The mixing chamber 7 is here shown provided at its opposite ends with truncated cone-shaped inlet pipes 13 with the smaller ends of said pipes extending into the chamber 7 as is clearly shown in Fig. 1. These members 13 are designed to form inlet nozzles for discharging into the mixing chamber 1 air and gas, the gas being fed thereto through tips or spuds 14 arranged in the larger outer ends of said cone-shaped inlets. These spuds 14 are mounted on branch pipes 65 15 which are connected with a main gas sup-

ply pipe 16. As shown, these spuds 14 are mounted in U-shaped brackets 17 which span the outer ends of the cone-shaped inlets 13, and the free ends of the legs thereof are secured to said inlets and to the outer 70 ends of the mixing chamber 7 by bolts or any other suitable fastening elements which assist in retaining said cone-shaped inlets in position within the mixing chamber 7, said members 13 being here shown as provided at 75 their outer ends with flanges 13' which are crimped around the outer ends of the casing forming the mixing chamber 7.

As shown, the spuds 14 are made in the form of reduced extensions mounted on 80 threaded pipes 18 and which are secured to the brackets 17 by clamping nuts 19 disposed on one side or face of the bracket and a shoulder 20 carried by the pipes 18 arranged on the outer faces of said brackets 85 as is shown clearly in Fig. 2. These spuds or tips 14 are mounted on the free ends of the branch pipes 15 which are here shown in the form of U-shaped couplings which are connected with the main pipe 16 by extensions 15' which extend laterally in opposite directions from said main pipe 16 so as to position said U-shaped pipes 15 at the ends of the mixing chamber 7 with the spuds disposed in position at the mouth or larger 90 ends of the inlet cones 13.

Each of the spuds 14 is provided with a gas valve 21 which is shown formed of a screw threaded rod having an actuating handle at its outer end and which extends 100 through the spud 14 and is designed to control the flow of gas through the opening of said spud.

From the above description it will be observed that a burner is produced provided 105 with a plurality of air inlet and mixing cones which discharge in opposite directions into a mixing chamber 7 and the air and gas entering therethrough in opposite directions, meet substantially midway the 110 length of the chamber 7 and the two streams impinge against each other becoming thoroughly mixed before passing out through the opening 5 into the cylinder 1 below the distributing or baffle plate 11 where it is further 115 broken up and mixed before passing out around the ends of said plate from which it passes through the apertures 4 to the outside of the burner ready for ignition. The plurality of rows of outlets for discharging the 120 gas from the burner which are spaced apart a sufficient distance to provide for the drawing of fresh air into the space between them, provides for the production of a flame which retains and consumes all of the poison such as carbon monoxide contained in the gas and hence insures perfect combustion and avoids all danger of monoxide gas poisoning. The arrangement of the cone shaped inlets in the 125 opposed ends of the mixing chamber 7 also 130

provides for the suction of a large amount of air into said chamber by the gas as it enters the cones through the spuds 14.

In the embodiment illustrated in Figs. 7 to 9, a slightly different form of burner is shown although the principle of operation thereof is the same. This burner comprises a flame tube 1' here shown cylindrical in form and closed at both ends the same as in the form shown in the other figures. This flame tube or casing 1' is provided on its top or upper portion with a plurality of series of laterally spaced longitudinally extending rows of perforations 4^a here shown 15 extending from end to end of the casing, the space 4^b between said series being designed to admit fresh air to the burning gas in the same manner as that described relative to the burner shown in the other figures. This 20 cylindrical casing 1' is shown provided in its bottom wall or the wall diametrically opposite the perforated wall thereof, with a plurality of longitudinally spaced inlets as 5', three of which are employed in the structure here shown and arranged in longitudinal alinement, although obviously any desired number may be employed. These inlets as 5' are designed for the admission of the fuel to the cylinder 1' in the form of air 25 and gas as will be hereinafter more fully described. Extending laterally from the casing 1' with their smaller ends engaging the openings 5' is a plurality of cone-shaped mixing chambers 7' to the larger ends of which are secured gas supply pipes 22. These pipes 22 are shown mounted in brackets 23 connected with the mixing chambers 7' at diametrically opposite sides to provide sufficient space at the ends of said 30 chambers for the free passage of air thereto. These pipes 22 as shown are substantially L-shaped with one arm thereof connected with a main supply pipe 24. The arms of these supply pipes which extend into the 35 chambers 7' are provided with spuds 14' similar to those shown and described in the other figures and each of which is provided with a gas valve 21' for controlling the flow of gas through the opening in the spud. Arranged within the casing 1' between the inlet and discharge openings thereof, is a longitudinally extending horizontally disposed partition 11' which is shown provided on its 40 opposite side edges with right angular attaching flanges 12' which are held in engagement with the opposed side walls of the cylinder 1' by means of the offset side edges of the shells 1^a and 1^b which are the same as those shown in the form above described 45 (see Figs. 7 and 8). This partition is designed as a deflector or distributor for the air and gas admitted through the openings 5' which impinges against said partition and spreads outwardly toward the opposite 50 ends thereof in the same manner as in the

form shown in the other figures, passing out through the openings 4^a in the top thereof where it is ignited and forms the flame of the burner.

Applicant by employing a plurality of 70 cone-shaped mixing chambers provides for the admission of a maximum quantity of air with the gas admitted through said chambers so that perfect combustion by the burner is insured. 75

I claim as my invention:

1. A gas burner comprising a closed casing having an inlet opening in one side wall thereof, a mixing chamber mounted on said casing and communicating with said inlet 80 opening, said mixing chamber being open at its opposite ends and having truncated cone shaped inlets arranged therein with their smaller ends extending into said chamber and discharging thereinto in opposite 85 directions, and means for injecting air and gas into the mouths of said cone-shaped inlets.

2. A gas burner comprising a closed cylindrical casing having a plurality of longitudinally extending laterally spaced series of rows of perforations formed in one side wall thereof and having an opening therein in its opposed side wall, a horizontal partition arranged in said casing between said 95 opening and said perforations, a tubular mixing chamber mounted on said casing around said opening, said mixing chamber being open at its opposite ends, truncated cone shaped inlets disposed in said ends 100 with their larger outer ends arranged at the ends of said chamber and their smaller ends extending inwardly thereinto and arranged opposite each other to discharge in opposite directions, U-shaped brackets spanning the 105 outer ends of said mixing chamber with the free ends of the legs thereof secured thereto, gas discharge spuds mounted in the cross bars of said brackets and disposed at the larger outer ends of said truncated cone 110 shaped members, U-shaped pipes having said spuds carried in one end thereof and extensions at their other ends extending laterally toward each other and arranged in longitudinal alinement and in a plane parallel with said mixing chamber, and a main gas supply pipe communicating with the inner ends of said extensions. 115

3. A gas burner comprising a closed cylindrical casing having a plurality of discharge openings in one side wall thereof, the opposed side wall being slit longitudinally and transversely to form flaps, said flaps being bent outwardly and shaped to form the opposed side walls of a mixing 120 chamber, a connecting strip inserted between the free edges of said flaps and secured thereto, said flaps extending a portion of the length of said casing and spaced at their opposite ends from the opposite ends 125 130

of said casing, truncated cone shaped inlet pipes mounted in the ends of said mixing chamber with their smaller ends extending into the chamber and their larger ends provided with flanges crimped around the outer ends of the mixing chamber, and means for injecting air and gas to the mouths of said cones.

4. The combination with a gas burner, of
10 a mixing chamber therefor having oppositely disposed inlets, truncated cone shaped members arranged in said inlets with their smaller ends extending into said chamber and arranged opposite each other to discharge in opposite directions into said chamber, and means for injecting air and gas into said cones through the larger ends thereof.

5. A gas burner comprising a cylindrical
20 casing closed at its ends and having perforations in one side wall thereof, semi-cylindrical shells arranged in said casing said shells being spaced apart at their inner ends to form an inlet for said casing, a horizontal
25 partition disposed in said casing and supported by said shells, and means for supplying fuel to said casing through said inlet.

6. A gas burner comprising a cylindrical casing closed at its ends and having perforations in one side wall thereof, the opposed
30 side wall of said casing being slit longitudi-

nally, semi-cylindrical shells arranged in said casing over the slit therein, said shells being spaced apart at their inner ends to form an inlet for said casing, the outer ends 35 of said shells being spaced from the ends of the casing and having longitudinally extending tongues for closing the slit portion of said casing beyond said shell ends, a horizontal partition disposed in said casing and 40 supported by said shells, and means for supplying fuel to said casing through said inlet.

7. A gas burner comprising a cylindrical casing closed at its ends and having perforations in one side wall thereof, the opposed side wall of said casing being slit longitudinally, semi-cylindrical shells arranged in said casing over the slit therein, said shells being spaced apart at their inner ends to 50 form an inlet for said casing, and a horizontal partition disposed in said casing and having depending flanges, said shells having pockets in their side edges to receive the flanges of said horizontal partition. 55

In testimony whereof I have hereunto set my hand in presence of two subscribing witnesses.

BENJAMIN C. BARTLEBAUGH.
